AIR CLEANER FOR KNITTING MACHINES

Robert C. Reinhardt and Fred L. Hefner, Newton,
N. C., assignors to Clyde Fabrics, Inc., Newton,
N. C., a corporation of Delaware

Application September 14, 1951, Serial No. 246,646

4 Claims. (Cl. 66—168)

1

This invention relates to an improved air cleaner for a circular knitting machine and more especially to a cleaning mechanism for such machine having a rotating needle cylinder and stationary needle control elements.

It is an object of this invention to provide a relatively simple and economically constructed cleaning mechanism for knitting machines of the type described wherein the knitting machine has a plurality of circularly spaced groups of needle control elements thereon, and said cleaning mechanism including a means which rotates with the needle cylinder and is positioned above the needle control elements and which will direct blasts of compressed air downwardly onto each of the groups of the needle control elements successively to thereby clear away lint or foreign matter which may collect on the needle control elements.

It is another object of this invention to provide an improved air cleaner for circular knitting machines, said knitting machines being characterized by a driven rotating needle cylinder with circularly spaced groups of needle control elements positioned adjacent and generally above the needles and said knitting machine also having a rotatable cloth rack disposed thereabove to which the knitted fabric is directed from the needles, and said cloth rack having take-up means thereon for taking up the fabric as it is knitted. The improvement includes an improved bearing structure disposed at the upper end of the cloth rack and which assists in supporting the upper end of the cloth rack for rotation in unison with the needle cylinder and a unique rotary connection in said bearing which has a pipe extending from a suitable source of compressed air connected to the upper end thereof and to the lower end of which connection a second pipe is connected to direct compressed air through the rotary connection. The second pipe extends downwardly along one side of the cloth rack and is bent inwardly to form a horizontally disposed portion at a point above the upper surfaces of said needle control elements, and this horizontally disposed portion of the second pipe is provided with downwardly directed perforations or openings therein thus comprising a nozzle. Thus, upon rotation of the needle cylinder and the cloth rack, the second pipe will rotate therewith to thus cause the nozzle portion thereof to pass above the groups of needle control elements successively to direct blasts of compressed air downwardly onto the same for removing lint or other foreign matter therefrom.

2

Some of the objects of the invention having been stated, other objects will appear as the description proceeds when taken in connection with the accompanying drawings, in which—

5 Figure 1 is a fragmentary elevation of a circular knitting machine of the type having a cloth rack disposed thereabove with means for taking up the knitted fabric from the needle cylinder disposed therebelow as the fabric is knitted and showing the improved air cleaner in association therewith;

10 Figure 2 is an enlarged vertical sectional view of the bearing, showing the improved rotary connection for directing compressed air through the bearing to the pipe which, in turn, directs blasts of compressed air onto the needle control elements and being taken substantially along the line 2—2 in Figure 1;

15 Figure 3 is an enlarged fragmentary elevation with parts in section of the lower portion of the tube shown in the left-hand central portion of Figure 1.

20 Referring more specifically to the drawings, the numeral 10 broadly designates the frame of a circular knitting machine of the type substantially as that manufactured by Tompkins Bros. Company, Syracuse, New York, and which is generally known as a table model Tompkins Double Head Spring Needle Knitting Machine.

25 The frame 10 includes a standard 11 which rests upon a table top 12, this table top having suitable mechanisms, not shown, disposed therebeneath for driving a conventional needle cylinder 13 which is rotatably mounted on a base 14.

30 The table also supports at least two groups of circularly spaced needle control elements, each of the two groups shown in Figure 1 being generally designated at 15 and 16, respectively. These groups of needle control elements 15 and 16 and the needle cylinder 13 are of well known construction and a detailed illustration and description thereof is deemed unnecessary. It

35 might be stated, however, that the needles in the needle cylinder 13 are controlled by the spaced groups of needle control elements 15 and 16 in a well known manner to form a tubular fabric 17 which extends upwardly substantially above the needle cylinder 13 and is taken up by a conventional take-up mechanism associated with a cloth

40 rack broadly designated at 20.

45 The cloth rack 20 is substantially rectangular in shape and includes upper and lower respective horizontal frame members 21 and 22 and side frame members 23 and 24. The upper horizontal frame member 21 is supported for rotation, in a

50 55

manner to be later described, in an outwardly extending arm 25 located at the upper end of the standard 11. It will be noted that as the fabric 17 passes upwardly from the needle cylinder 13 to the cloth rack 20, it encircles a spreading member 20a which is usually elliptically-shaped and which is supported on a hub member 20b suitably secured to the upper end of a driven vertically disposed shaft 20c, this shaft 20c being driven by conventional means, not shown, at the same rate as that of the needle cylinder 13. The spreading member 20a has the lower ends of upwardly diverging arms 20d and 20e thereon which are disposed within the tubular knitted fabric 17 and which bear against the lower horizontal frame member 22 of the cloth rack 20 to thereby cause the cloth rack 20 to rotate in unison with the needle cylinder 13, the cloth rack 20 being disposed in axial alignment with the needle cylinder 13.

The side frame members 23 and 24 support opposed ends of a cloth roll 27 for rotational and vertical sliding movement therein, and as the cloth 17 is wound onto the roll 27, this portion of the cloth surrounding the roll 27 rests against a driven take-up roll 30, reduced opposed ends of which are rotatably mounted in the side frame members 23 and 24. The cloth 17 also extends upwardly between the lower frame member 22, and an intermediate rod 31 and an idler roll 32 prior to passing over the roll 30 and then about the cloth roll 27. The idler roll 32 and the rod 31 may be rotatably mounted in the side rails or side frame members 23 and 24. The left-hand end of the roll 30 in Figure 1 has a hand wheel 34 thereon for manually taking up the slack in the tubular fabric 17.

The reduced right-hand end of the take-up roll 30 has a ratchet wheel 35 fixed thereon which is intermittently driven by a ratchet pawl 36, this ratchet pawl 36 being pivotally mounted on the reduced right-hand end of the roll 30. The ratchet pawl 36 is driven in a reciprocatory manner by means of a lower connecting rod extension 37 and an upper connecting rod extension 40, which are provided with respective collars 41 and 42 fixed thereon, between which a compression spring 43 is disposed. The proximate ends of the connecting rod extensions 37 and 40 are normally spaced apart from each other so that movement of the rod extension 40 may be permitted relative to the rod extension 37 depending upon the tautness of the fabric 17. These connecting rod extensions 37 and 40, the collars 41 and 42 and the compression spring 43 may be collectively referred to as a connecting rod.

The upper end of the connecting rod extension 40 is pivotally connected, as at 45, on an eccentric arm 46 fixedly mounted on a shaft 47 which extends inwardly and is rotatably mounted in bearing blocks 58 and 51 suitably secured to the upper surface of the upper frame member 21 of the cloth rack 20.

The inner end of the shaft 47 has a stationary beveled gear 53 fixed thereon which meshes with a beveled gear 54 fixedly mounted on a reduced portion 55 (Figure 2) of a boss or hub portion 56 at the outer end of the arm 25.

It is thus seen that, upon rotation of the cloth rack 20 and the needle cylinder 13, the stationary beveled gear 54 will cause the beveled gear 53 to rotate thereby causing the connecting rod, including the elements 37, 40, 41, 42 and 43 to thereby impart pivotal movement to the pawl 36 and to thereby impart intermittent rotation

to the take-up roll 30 and to thus cause the cloth or fabric 17 to be wound about the cloth roll 27.

The hub or boss portion 56 of the arm 25 of the frame 10 has a vertically extending bore 60 therethrough in which a shaft 61 is rotatably mounted. The upper end of the hub portion 56 of the arm 25 of the frame 10 has a counterbore 62 therein in which a thrust bearing member 63 is disposed, this bearing member 63 being fixedly secured to the upper end of the shaft 61 and resting upon and in sliding rotational engagement with the shoulder formed at the juncture of the bore 60 and the counterbore 62.

The lower end of the shaft 61 has an enlarged portion 64 integral therewith which penetrates the upper frame member 21 of the cloth rack 20 and a shoulder 64a formed by the juncture of the shaft 61 and the enlarged portion 64 on the lower end thereof supports the cloth rack 20. The upper frame member 21 of the cloth rack 20 is held against the shoulder 64a of the shaft 61 by a collar 65 which is fixedly mounted on the shaft 61. Thus, the shaft 61 supports the bar or upper frame member 21 of the cloth rack 20 for rotation in the hub portion 56 of the arm 25.

The parts heretofore described are the usual parts of a knitting machine, except that shaft 61 is provided with a passageway 84 to cooperate with the new parts added, and it is with these parts that the present invention is particularly adapted to be associated. In view of the fact that the improved air cleaner, to be presently described, rotates with the cloth rack 20, it is necessary that compressed air initially be directed to the improved air cleaner at the axis of the cloth rack 20. To this end, there is provided an improved rotary union comprising a stationary housing 71 which is provided with a passageway 72 in the upper end thereof to which a pipe 73 extending from a suitable source of compressed air, not shown, is suitably connected for communication therewith.

There is disposed below the passageway 72 in the housing 71 an enlarged air chamber or bore 74 which is provided with a shoulder 75 against which the outer race of a ball bearing 76 is disposed. Any type of anti-friction or a friction bearing may be employed in lieu of the ball bearing 76, this ball bearing being shown by way of illustration only. The inner race of the ball bearing 76 is fixed on the upper end of a conduit or pipe 80 by any suitable means such as by a pressed fit and this pipe 80 extends downwardly and loosely penetrates a cup-shaped gland member 81 which is threadably mounted on the lower end of the housing 71.

The pipe or conduit 80 extends downwardly beyond the gland 81 and slidably penetrates a dome-like cap 82 and then is threadably embedded in the upper end of the shaft 61 heretofore described. The shaft 61 is provided with a longitudinally extending passageway 84 therein which communicates with the pipe or conduit 80 and directs compressed air downwardly through the passageway 84 to an elbow 85 which is suitably secured in the lower end of the shaft 61 as by being threaded thereinto. This elbow has one end of a pipe 86 connected thereto.

The dome-shaped cap 82 is a usual part of knitting machines of this type but has been modified to permit the pipe or conduit 80 to extend therethrough and also has supporting means such as a plurality of circularly spaced rods or bars 90 suitably secured thereto, as by weld-

ing. These rods or support members 90 extend upwardly and are suitably secured, as by welding, to the gland 81 to thereby support the gland 81. The gland 81 is provided in order to permit the air chamber housing 71 to be quickly removed from the same by merely turning the same out of the gland member 81. This facilitates the removal of the conduit or pipe 80 and the housing 71 as well as the pipe 13 from the hub portion 56 of the arm 25. The dome-like cap member 82 is suitably secured to the upper end of the hub portion 56 in the arm 25 by any suitable means such as set screws 91.

The pipe or tube 86 extends from the elbow 85 outwardly adjacent the horizontal frame member 21 of the cloth rack 20 and is then bent downwardly to form a vertical portion 86a which extends adjacent the vertical frame member 23 of the cloth rack 20. The portion 86a is then bent inwardly adjacent the lower horizontal frame member 22 of the cloth rack 20, forming a portion 86b which is then bent downwardly adjacent the cloth or fabric 17 to form a stem portion 86c. This portion 86c is bent inwardly towards the fabric to form a horizontal nozzle portion 86e which is closed at its outer end, as at 92 (Figure 3), and the lower wall of which is provided with a plurality of ports or exhaust openings 93 through which the compressed air is emitted and directed onto the groups of needle control elements 15 and 16 as the needle cylinder 13 and the cloth rack 20 rotate in unison.

It is thus seen that I have provided an improved air cleaner for circular knitting machines of the type wherein the fabric or knitted material passes upwardly from the rotating needle cylinder to a cloth rack and wherein the knitting machine is provided with a plurality of circularly spaced groups of needle control elements, to thus successively remove accumulations of lint and other foreign material from the groups of needle control elements to thereby obviate the necessity of stopping the machine for cleaning or for repair as a result of accumulations of lint causing breakage of various parts of the machine, such as the needles. It is evident that this will greatly increase the length of operation of the machine compared to knitting machines of this type which have heretofore been in use and will result in a higher quality of fabric than has heretofore been the case.

In the drawings and specification there has been set forth a preferred embodiment of the invention and although specific terms have been employed they are used in a generic and descriptive sense only and not for purposes of limitation, the scope of the invention being defined in the claims.

We claim:

1. An improved air cleaner for circular knitting machines of the type having a rotating needle cylinder and also having circularly spaced groups of needle control elements disposed adjacent the needle cylinder and also having a cloth rack spaced above the needle cylinder and said cloth rack being rotatable with the needle cylinder and wherein the fabric knitted by the needle cylinder is directed upwardly to the cloth rack to be taken up thereby, said knitting machine also having a frame member disposed above the cloth rack and a vertically disposed shaft rotatably mounted in the frame member for supporting the upper portion of the cloth rack for rotation, said shaft having a longitudinally extending passageway therethrough, said shaft having a pipe con-

nected to the upper end thereof, a fixed housing disposed above said pipe and into which the pipe projects, a sealed bearing in said fixed housing through which the upper end of the pipe projects, means for conducting compressed air to the interior of said fixed housing, a pipe connected to the lower end of said shaft and communicating with the passageway in said shaft, said pipe being shaped to conform substantially to the configuration of the cloth rack and extending along the upper edge thereof and then being bent downwardly to extend along one side thereof and then being bent inwardly at its lower end to form a nozzle portion, said nozzle portion being disposed immediately above the upper surfaces of said needle control elements, said nozzle being closed at its free end adjacent the knitted fabric and having a plurality of perforations in the bottom surface thereof whereby compressed air will pass through the passageway in said shaft and thus through the pipe to be emitted from the perforations in said nozzle and whereby said pipe and its nozzle will rotate with the cloth rack to thereby successively direct blasts of compressed air onto the spaced groups of needle control elements for removing lint and foreign matter therefrom.

2. An improved air cleaner for circular knitting machines of the type having a rotating needle cylinder and also having circularly spaced groups of needle control elements disposed adjacent the needle cylinder and also having a cloth rack spaced above the needle cylinder and wherein the fabric knitted by the needle cylinder is directed upwardly to the cloth rack to be taken up thereby, said knitting machine also having a frame member disposed above the cloth rack and a shaft rotatably mounted in the frame member for supporting the upper portion of the cloth rack for rotation; said shaft being tubular, means for directing compressed air to the passageway in said shaft comprising a stationary housing spaced above the frame member and means on said frame member for supporting said housing in spaced relation to the upper end of said shaft, said housing having an air chamber therein, a source of compressed air connected to said housing and communicating with said air chamber, a bearing member mounted in the air chamber, a conduit mounted for rotation in said bearing member and extending downwardly therefrom, and the lower end of said conduit being connected to the upper end of said shaft for communication with the passageway in said shaft, whereby compressed air may flow from the source thereof through the air chamber and thus through the conduit to the passageway in the shaft to thus be directed to the pipe having the nozzle thereon.

3. In a circular knitting machine having a rotatable needle cylinder and groups of needle control elements adjacent said needle cylinder and said machine also having a frame with an arm portion and a cloth rack for taking up the fabric from said needle cylinder and being spaced above said needle cylinder; an improved air cleaner for said needle control elements comprising said arm having a hub portion, a vertical shaft rotatably mounted in said hub portion, said shaft having a passageway therethrough, a first pipe connected to the upper end of said shaft and communicating with said passageway, a stationary housing supported by said hub portion and having an air chamber therein, the upper end of said first pipe being rotatably mounted in said stationary housing and communicating with said chamber, a

second pipe connected to said stationary housing and communicating with said chamber for introducing compressed air thereto, means securing the upper portion of said cloth rack to the lower portion of said shaft for rotation of the rack with said needle cylinder, and a third pipe connected to the lower end of said shaft and extending downwardly about said cloth rack and having a nozzle on the lower end thereof positioned adjacent the needle control elements, whereby, upon rotation of said cloth rack, said nozzle will pass adjacent said needle control elements and will direct air to said needle control elements to clear the same.

4. In a circular knitting machine having a rotatable needle cylinder and groups of needle control elements adjacent said needle cylinder and said machine also having a frame with an arm portion and a cloth rack for taking up the fabric from said needle cylinder and being spaced above said needle cylinder; an improved air cleaner for said needle control elements comprising said arm having a hub portion, a vertical shaft rotatably mounted in said hub portion, said shaft having a passageway therethrough, a first pipe connected to the upper end of said shaft and communicating with said passageway, a stationary housing supported by said hub portion and having an air chamber therein, the upper end of said first pipe being rotatably mounted in said stationary housing and communicating with said chamber, a second pipe connected to said stationary housing

and communicating with said chamber for introducing compressed air thereto, means securing the upper portion of said cloth rack to the lower portion of said shaft for rotation of the rack with 5 said needle cylinder, a third pipe connected to the lower end of said shaft and extending downwardly about said cloth rack and having a nozzle on the lower end thereof positioned adjacent the needle control elements, whereby, upon rotation 10 of said cloth rack, said nozzle will pass adjacent said needle control elements and will direct air to said needle control elements to clear the same, means permitting removal of said stationary housing comprising a gland loosely penetrated by 15 said first pipe and secured to said hub portion of said arm, said gland having an internally threaded portion on the upper end thereof, and said stationary housing being externally threaded at its lower end and threadably secured in internally threaded portion on the upper end of said gland.

ROBERT C. REINHARDT.
